UNITED STATES PATENT OFFICE.

ROBERT SANFORD RILEY, OF PROVIDENCE, RHODE ISLAND, ASSIGNOR TO SANFORD RILEY STOKER CO. LTD., OF WORCESTER, MASSACHUSETTS, A CORPORATION OF MASSACHUSETTS.

UNDERFEED FURNACE.

1,160,324.

Specification of Letters Patent. Patented Nov. 16, 1915.

Application filed October 20, 1911. Serial No. 655,823.

To all whom it may concern:

Be it known that I, ROBERT SANFORD RILEY, a citizen of the United States, and resident of Providence, in the county of 5 Providence and State of Rhode Island, have invented certain new and useful Improvements in Underfeed Furnaces, (Case C), of which the following is a specification.

This invention relates to furnaces and automatic mechanism for supplying fuel there-to on the underfeed principle, and has for its purpose primarily to effect a positive feed of fuel and refuse to the part of the furnace whence the refuse is discharged; to 15 automatically break up lumps of fuel and refuse, and make the fuel bed homogeneous; and simultaneously and automatically remove deposits of clinker or slag from the furnace walls, as explained in applications 20 filed concurrently herewith, numbered 655,821 and 655,822 respectively.

More particularly, the object of the specific embodiments of my invention described and claimed herein (in which these embodiments are distinguished from those described in the companion applications referred to) is to provide, in a construction in which the floors of the retort or retorts supporting the fuel within the furnace are 30 stationary, air-supplying bounding walls for such retorts movable oppositely to one another to effect the purposes above set forth. That is, the air-supplying means constituting one side of any retort is distinct 35 from the corresponding means constituting the other side of the retort, and is moved simultaneously with and in directions opposite to the movements of such other means. With this construction, where two or more 40 retorts occur in a furnace, the entire air-supplying means between adjacent retorts, forming in effect a common wall for both retorts, is a unit and moves as such, while the parting line or division between retorts 45 occurs in the retort itself instead of between the walls of two retorts.

Another feature covered in the present application consists in a provision by which refuse may be continuously discharged from 50 the furnace as fast as it accumulates.

In the drawings forming a part of this application: Figure 1 represents a longitudinal section of a furnace in which the spe-

cial features above noted are embodied. Fig. 1^a is an enlarged elevation of a detail of the 55 operating mechanism. Fig. 2 is a plan view of a part of such furnace, showing two of the retorts thereof. Fig. 3 is a part front elevation and part vertical cross section of the retorts shown in Figs. 1 and 2, the cross 60 section being taken on line 3-3 of Fig. 1. Fig. 3^a is a sectional view of the air-supplying boundary between two retorts, on line A-A of Fig. 1. Fig. 4 is a rear elevation of one of the retorts. Fig. 5 is a detail view 65 in side elevation of an adjusting means for governing the rate of discharge of the refuse. Fig. 6 is a view similar to Fig. 1, of another form of the invention embodying the same principles, taken on line 6-6 of 70 Fig. 7. Fig. 7 is a plan view of the same. Fig. 8 is a longitudinal section of one of the air-supplying means forming a side of a retort or a parting wall between two retorts on line 8-8 of Fig. 7. Fig. 9 is in part a 75 front elevation and in part a section on line 9-9 of Fig. 6, of the embodiment of the invention shown in Fig. 6. Fig. 10 is a side elevation of the furnace, showing mechanism for moving the air-supplying retort 80 walls.

Referring first to Figs. 1 to 5 inclusive, the furnace is shown as consisting of stationary inclosing walls and one or more retorts contained within the space inclosed by 85 the walls. 1 represents the front wall, and 2 the bridge wall at the rear of the fire space. Each retort is a pocket or trough between two side walls into which the fuel is fed when first being introduced into the fire 90 and in which it is distilled before the solid combustible portion is ignited. The walls of the retort are formed by air boxes or conduits which are sufficiently separated to leave fuel channels between them. The 95 conduits rest upon an air trunk 3 which crosses the furnace, and they have downwardly-extending substantially vertical walls bearing upon the upper side of the air trunk. Those conduits which are placed 100 in the furnace next to the side walls have their outer boundaries formed by vertical plates or walls, as indicated at 4 in Fig. 3. The interior boundary of each of the conduits consists of a wall 5 which is in a ver- 105 tical plane from the top of the air trunk

to a line *a*—*b* shown in Fig. 1, and to the front end of the conduit. Above the line *a*—*b* is a wall 6 which flares outward and upward and forms one side of the retort. 5 When two such conduits are placed in proper position in the furnace, their corresponding walls 5 lie in contact, as shown in Fig. 3, and their walls 6 define a trough. The adjacent conduits continue in 10 contact from the line *a*—*b* to their extreme lower and inner ends. Forward of the point *b* they are separated and the bottom or floor of the retort is constituted by a plate 7 which fits closely between the walls 15 6. Such plate is secured to the lower wall of a tubular member 8 which I term a fuel conduit because fuel is fed therefrom into the retort. The air conduit between two adjacent retorts is formed as shown in Fig. 20 3^a, having approximately twice the width of the conduit shown at the right of Fig. 3 and being without the vertical side wall 4.

At the ends of the upright walls which rest on the air trunk are end walls which 25 inclose a box communicating with the interior of the conduit and overlying an opening 9 in the air trunk (Fig. 3). These inclosing walls are adapted to slide across the top of the air trunk, whereby the conduit is enabled to move bodily back and forth in a substantially horizontal line.

The tops of the walls which form the sides of each air conduit are unconnected, or, in other words, the upper side of the 30 conduit is open. Such opening resembles a longitudinal slot. Over the longitudinal opening are placed boxes 10 which permit escape of air from the conduit in such a manner as to mingle most effectively with the fuel, and may be termed nozzles. These boxes are open at the bottom and rear and have walls at their opposite sides, at the top, and at the front. When placed close together over the longitudinal opening of the conduit their side walls rest upon the edges of this longitudinal opening so that their interiors are in communication through their open bottoms with the interior of the conduit, and their rear sides 35 are partly blocked by the front walls of the next adjacent boxes. As the front wall of each box is slightly shorter than the open rear side of the next, a slit is left at the top through which air may flow toward the rear of the furnace. Projecting from the top wall of each box is a lip 11 overlying such slit and the top of the next box, which deflects the air and causes it to flow laterally through the fuel before it rises. In the 40 side walls of each box are outlets 12. This last statement applies to the boxes which lie between two retorts. Those boxes at the outer sides of the outermost retorts have outlets through their inner walls only, and 45 not through their outer walls.

The fuel conduit 8, previously mentioned, is mounted upon a bracket 13 secured to the air trunk and projecting forwardly therefrom. It has an opening 14 in its top wall over which is placed a hopper 15. A pusher 70 or plunger 16 is adapted to reciprocate in the tube and across the opening 14, thereby alternately allowing fuel to fall through the opening and pushing such fuel into the furnace. The plane of the floor plate 7, 75 and of the bottom wall of the tube 8, which is a continuation of such floor plate, is below the line of outlets from the boxes or nozzles 10. Consequently the fuel when it first enters the retort through the fuel conduit is below the points at which air is fed to the furnace and below the burning fuel bed. It is gradually pushed rearwardly and upwardly across the air inlets into the zone of combustion by the combined action 80 of the feeding pusher 16 and the movement of the walls.

Movement is imparted to the air conduits and outlet boxes by any suitable means, such, for instance, as a shaft 17 on which are 90 cranks or eccentrics 18, 19, acting upon eccentric rods 20, 21, which are connected to adjacent conduits. These eccentrics are positioned oppositely to one another on the shaft, hence cause the conduits which form 95 the opposite walls of the same retort to be moved simultaneously in relatively opposite directions. The pusher 16 is also conveniently driven from the shaft 17, being actuated by a pinion on the latter which meshes 100 with a gear 22 on a countershaft 23, the gear carrying a crank pin 24 which drives a connecting rod 25 pivoted to the pusher.

The fuel which is fed through the fuel-conducting tube 8 by the pusher 16 issues 105 into the forward end of the retort and is supported by the floor 7 below the line of air outlets from the nozzle boxes 10. The edges of the retort walls on which the boxes 10 rest are preferably inclined downwardly 110 from front to rear and the line of boxes is similarly inclined. These boxes define the mouth of the retort. The slope of the retort mouth is less than sufficient to cause material of the nature of coal to slide, and the slope 115 of the retort bottom is still less. The latter may even be approximately horizontal if desired. The line of the retort bottom therefore intersects the line of the retort mouth, and the bottom is set at such a height and is 120 so limited in length as to terminate above and in front of the rear ends of the air conduits.

At the rear end of each air conduit I provide outlet boxes 26 of different character from 125 those previously described and designated by the numeral 10. The boxes 26 are so constructed that their ends extend beyond the end or sides of the boxes 10 and terminate at the middle of the retort. In order to dis- 130

tinguish these boxes from the boxes 10, I may call them bars. The bars carried by adjacent conduits meet at the center line of the retorts and are adapted to support the fuel which issues from the rear end of the retort. These bars are open at the rear and are provided with lips extending rearwardly from their top walls whereby to form slits, rearwardly directed, between adjacent bars. 5 The bottoms are open only where they overlap the longitudinal slots of the respective conduits whereon they are supported, and their end walls have no outlet openings. Consequently the bars 26 provide practically 10 continuous horizontal slits extending from side to side of the furnace, through which air may flow to aid combustion of that fuel which is fed over the bars.

I will now describe the manner in which 20 the fuel is fed by the moving conduits. The feeding capacity of the pusher 16 is sufficient to fill the forward end of the retort and push the fuel beyond the mouth of the retort, whence the fuel overflows the retort 25 sides and rests on the tops of the flanking outlet boxes. When the conduits with their supported boxes move rearwardly they carry the fuel resting upon them and bearing against their side walls toward the rear. On 30 their return movement toward the front of the furnace the fuel is prevented from following by reason of the resistance of the fuel continually entering through the feed tube 8, and of the sloping floor 7. Such of the fuel 35 as lies over the tops of the outlet boxes is left unsupported and drops directly downward upon the lower boxes. In this way a constant step-by-step rearward feed of the fuel in the retorts is accomplished. As the 40 conduits which form the opposite sides of the same retort move at once oppositely to one another, the fuel is kept in continuous agitation at the same time that it is advanced, and thereby is broken up and the 45 particles distributed about in such a way as to fill holes in the fire and form a fuel bed of even thickness and homogeneous character. The conduits adjacent to the side walls of the furnace travel relatively to such walls 50 and cause any deposits of slag which may form upon these walls to be broken off.

Where two or more retorts are provided in the same furnace, the intermediate air conduit is made as a single unit and moves 55 with its supported outlet boxes as a unit. Thus the walls and air-supplying means common to the retorts form a unit distinct and independent from the units constituting the other walls of these retorts and movable 60 simultaneously with and oppositely to such units. The retort itself is thereby divided into three parts, to wit, a stationary bottom and independent and oppositely moving walls. The division between the oppositely 65 moving parts in rear of the retort proper is

on the central vertical plane of the retort, such plane being represented by the line *c-d* in Fig. 2.

After being fed out from the retort mouth and carried over the bars 26 in rear of the 70 retort, the refuse falls upon a dumping plate 28 pivoted by a rock shaft 29 held in brackets 30 projecting from the rear side of the air trunk. The conduits carry refuse pushers 31 to force the ash and other incom- 75 bustible residue of feed along the dumping plate toward the bridge wall. The pivotal axis of the dumping plate is near the refuse pusher, so that the swinging edge of the plate is the part most remote from the 80 pusher. By tilting the plate about its axis, the refuse accumulated thereon may be discharged into an ash pit.

It is part of my invention to arrange for an automatic, continuous and gradual discharge of the ash from the dumping plate to avoid the necessity of periodical attention and possibility of more or less loss of unburned fuel with the ash. Accordingly, I have provided an opening above and at the 90 rear of the dumping plate between the same and the bridge wall and directly in rear of the pushers 31. The latter, reciprocating, push the refuse in small quantities through the opening into the ash pit. By the time 95 the refuse reaches this point practically all the combustible is consumed. The area of the opening is varied in accordance with the quantity of ash to be disposed of, by adjustment of the dumping plate about the 100 axis of the rock shaft 29, such adjustment being made by a controlling lever 34 connected to the plate by an arm 32 fixed to the rock shaft, and an intermediate link 33; and the adjustments are maintained by a 105 stop adapted to be engaged by the lever, which stop may be set in any one of a series of holes 36 in an arc 35, concentric with the pivot of the lever. The same control lever also serves to tilt the plate so as to discharge 110 the entire accumulation of ash thereon. A weighted shutter 38 is pivotally hung across the opening to prevent flow of air therethrough over the fire.

The rate of the feed is governed by the 115 extent of movement given to the air conduits, which can be regulated. A convenient means for such regulation is shown in Figs. 1 and 1^a, and consists in providing lost motion between the eccentric rods 20, 21, 120 etc., and the eccentric straps with which they are arranged.

39 represents the eccentric strap, which is provided with a socket 40 receiving one end of the eccentric rod. The socket may move 125 telescopically upon the end of the eccentric rod to an extent limited by the length of the slot 41 in the socket through which a pin 42 carried by the rod projects.

43 represents blocks or shims which may 130

be placed in the socket across the slot between the pin 42 and either end of the slot 41, thus limiting the effective length of the slot and diminishing the extent of lost motion. According as the lost motion is great or small, the conduits are given a less or a greater amount of travel. In this way the rate of feed and the rate of disposal of refuse is regulated in accordance with the proportion of incombustible material in the fuel, so that the refuse may be ejected as fast as it accumulates. The above described adjustment of the dumping plate permits the size of the outlet through which the refuse is ejected to be governed accordingly, and may be exactly great enough to permit a steady flow of refuse into the ash pit and to prevent banking up of the refuse.

The same general principles above described and explained are found in a modification of the invention illustrated in Figs. 7 to 10. In the latter figures the conduits forming the sides of the retorts are mounted to oscillate about a horizontal axis. The conduits are located on each side of a plate 44 constituting the bottom or floor of a retort, and the conduit between two adjacent retorts forms a common air-supplying means for said retorts and the common side walls thereof. One of the conduits, designated 45, is shown in longitudinal section in Fig. 8. It has vertical side walls and a bottom, but is open at the forward end and at the top. The side walls at the forward end are recessed so as to fit the circularly formed walls 46 which are secured upon the upper side of the air trunk 3 and are upright and in the planes of the conduit walls. Openings 47 are left in the top of the air trunk between the pairs of walls 46. Extending across from the walls of each pair are webs 48 which confine the air, causing it to flow from the trunk into the conduit. The walls 46 with the webs 49 form, in effect, boxes which are cylindrical segments and are open both into the air trunk and into the conduits. The side walls of the conduits are adapted to slide on the walls 46, and thus each conduit is movable as a unit oscillatively about the center of curvature of the meeting edges of such walls.

On the upper edges of the conduit walls and bridging the space between such edges, are outlet blocks 10 similar in purpose and construction to those already described in this specification and also described in the companion applications hereinbefore referred to. The series of boxes 10 extends entirely to the rear end of the conduit.

The floor 44 is below the mouth of the retort which is defined by the blocks 10, and extends in a direction intersecting the mouth. Its forward end is in extension with the fuel feeding tube or conduit 50 to which it is connected, and its rear end overlaps the

first one of a series of outlet or nozzle boxes 51 arranged between the conduits. The boxes 51 are supported upon the open end of an air flue 52 communicating with the air trunk 3 and projecting therefrom toward the rear of the furnace. The air-trunk flue 52, outlet boxes 51 and conduit floor are all stationary, while the conduits with the outlet boxes carried thereby are movable oscillatively.

Suitable mechanism is provided for oscillating the conduits, which is conveniently a rock-shaft 53 having arms 54, 55, connected by links 56, 57, with the several conduits respectively. The rock-shaft 53 may be driven from a main driving shaft 58 by a crank 59 (see Fig. 10) through a connecting rod 60, and an arm 61 secured upon the rock-shaft. The engagement between the rod 60 and arms 61 is effected through pins 62, 63, carried by the rod on opposite sides of the arm and adapted to be placed in different positions in holes 64 in the rod. The different settings of the pins permit more or less lost motion to occur between the rod and arm whereby the amount of motion given to the conduits and the rate of feed of the fuel may be varied.

In the tube 50 is a pusher 65 which travels under an opening 66 in the upper side of the tube and propels fuel delivered through this opening from a copper 67 into the forward end of the retort. The pusher is provided with an extension 68 lying upon the floor of the retort and having shoulders 69, 70, to assist in propelling the fuel after the same has entered the retort. The pusher and its extension and shoulders feed the green fuel into the retort below the openings from which the air conveyed through the conduits is discharged, and thence out of the mouth of the retort into the bed of burning fuel which extends over the outlet boxes. The fuel is thus introduced into the furnace on the underfeed principle. After issuing from the mouth of the retort, further feed of the fuel is accomplished positively through the movement of the retort walls, which are kept in constant motion. The relation of the walls to the axis of oscillation is such that at the rear of the retort they move up and down almost vertically, and at the front of the retort they move forward and back. Their motion keeps the fuel in agitation, breaking it up and continually impelling it toward the rear, where the ash falls upon a dumping plate 71 and is discharged from the latter into the ash pit.

The fuel which remains in the vertical zone of the retort floor is fed from the rear end of the latter over the boxes 51, where it is supplied with air. The floor of the retort is impervious to air, and while the fuel is on this floor it is below the line of air openings and is not ignited. By the time it

- reaches the inner end of the floor it has become converted into coke, free of volatile combustible, and is then carried over the boxes 51 of which the tops form a grated 5 fuel support where air is supplied to the fuel. As the opposite walls of the same retort travel simultaneously and oppositely to one another, and as the entire wall structure of two adjacent retorts moves as a unit, 10 in this embodiment of the invention as well as in that shown in Figs. 1 to 5, substantially the same effects are secured in this form of the invention as those already described.
- 15 Having thus explained the nature of my said invention and described a way of constructing and using the same, although without attempting to set forth all the forms in which it may be made or all the modes of 20 its use, what I claim is:
1. In a furnace a fuel burning retort, having a fuel inlet at one end and extending therefrom toward a refuse discharge point, said retort being formed in part of side 25 walls each of which is independent of the other and is mounted with capability for movement as a whole independently of the other, means for feeding fuel into the retort through the inlet thereof, and means for 30 moving said walls to propel the fuel and refuse in the furnace toward such discharge point.
  2. In a furnace, air conduits forming the sides of a fuel burning retort and having 35 outlets, each conduit being independent of the other and mounted with capability of movement independently as a unit, and driving mechanism for moving said conduits.
  - 40 3. In a furnace, a plurality of fuel burning retorts comprising upright side walls and floors independent of such side walls, the partition walls between adjacent retorts being movable as a unit, and mechanism for moving such partition walls alternately in opposite directions.
  4. In a furnace having outer air conduits forming the outer boundaries of a plurality of fuel retorts, an intermediate air conduit 50 dividing one retort from the adjacent one, forming the inner side walls of both retorts and being movably mounted, and mechanism for moving said intermediate conduit.
  5. In a furnace, outer walls forming the 55 outer boundaries of a plurality of fuel burning retorts, an intermediate dividing wall unit, between two adjacent retorts, mounted for movement independently of said outer walls, and means for so moving said intermediate wall unit, whereby to feed and disintegrate the fuel in the retorts.
  6. In a furnace having a plurality of fuel 60 burning retorts, an air conduit so arranged that its sides form the dividing walls of two adjacent retorts, said conduit having outlets
  - for discharge of air into the furnace and being mounted with capability of independent movement as a unit, and mechanism for so moving said conduit.
  7. In a furnace, a fuel burning retort having its side walls independent of each other and relatively movable, and mechanism for moving said retort side walls back and forth. 70
  8. In a furnace, a fuel burning retort having a stationary bottom and having side 75 walls mounted with provision for movement, said side walls being independent of each other and each mounted with capability for independent movement as a whole and means for moving said walls to feed and 80 break the fuel.
  9. A furnace including in its construction air conduits having substantially upright side walls and plates between said conduits, the plates forming floors of fuel burning retorts and the conduit walls forming the sides thereof, each of said conduits having air discharge outlets above the plates, and said conduits being mounted with capability of movement independently of each 85 other.
  10. In a furnace having a plurality of fuel retorts, and an air-conducting structure forming a partition dividing adjacent retorts from one another, means for feeding fuel into said retorts, and means for moving the entire air-carrying wall as a unit to propel the fuel in the retorts. 95
  11. In a furnace a plurality of separated upright air-conducting walls, between which 100 is a space forming a fuel retort, said walls at the opposite sides of the retort being movable bodily and capable of movement independently of each other, and means for moving each of said walls as a whole so as to 105 effect a feed of fuel and refuse from the retort.
  12. In a furnace having a fuel inlet and having also provisions for discharge of refuse at a point distant from such inlet, a 110 plurality of separated upright air-conducting walls, between which is a space forming a fuel retort, such walls being so placed that said fuel inlet opens into the retort, and the upper boundaries of the walls having a 115 downward slope from the inlet toward the discharge point of the furnace, said walls at the opposite sides of the retort being movable bodily and capable of movement independently of each other, and means for moving each of said walls as a whole so as to effect a feed of fuel and refuse from the retort. 120
  13. In a furnace, the combination of separated air-supplying means having outlets 125 at their upper portions and providing a fuel passage between them, means for supplying fuel to said passage, a refuse support in rear of and below said air-supplying means, refuse discharging means constructed and 130

arranged to propel refuse across and from said support, and means for varying the extent of movement of said refuse discharging means to vary the rate of discharge, said refuse support being adjustable so as to alter the capacity of the discharge outlet in accordance with the rate of discharge.

14. In a furnace, the combination of separated air-supplying means having outlets at their upper portions and providing a fuel passage between them, means for supplying fuel to said passage, a refuse support in rear of and below said air-supplying means, refuse discharging means constructed and arranged to propel refuse across and from said support, means for varying the extent of movement of said refuse discharging means to vary the rate of discharge, and means for so placing and holding said support as to enlarge or restrict the discharge outlet according to the rate of discharge.

15. A self-feeding furnace, comprising separated walls forming the sides of a fuel feeding passage and having outlets for emission of air at or near their upper limits, said walls being movably mounted, means for feeding fuel into said passage below said outlets, mechanism for moving the walls longitudinally of the passage to feed the fuel, a support arranged in rear of the passage to receive the incombustible residue of the fuel, and pushing means connected with said walls and movable therewith across said support to discharge the refuse therefrom, said support being adjustable to vary the capacity for discharge of the residue.

16. A self-feeding furnace, comprising separated walls forming the sides of a fuel feeding passage and having air outlets arranged to discharge air across the passage, said walls being movably mounted, means for feeding fuel into the passage, mechanism for moving the walls longitudinally of the passage to feed the fuel and refuse, the furnace having a refuse-discharging space at the rear of such passage, a refuse support arranged to bridge such space, and pushing means operated by said walls to feed the refuse of the fuel across said support, the support being adjustable so as to cover more or less of such space, and thereby control the effective size of such space according to the rate of discharge of the refuse.

17. A self-feeding furnace, comprising separated walls forming the sides of a fuel-feeding passage, said walls being movably mounted, mechanism for moving the walls longitudinally of the passage to feed the fuel and refuse, a rear furnace wall in rear of the passage and separated by a space therefrom, a refuse support extending to some extent across such space, pushing means operated by the fuel-feeding walls to feed refuse across said support and into

said space, means for varying the extent of movement of said pushing means, and means for adjusting the support to vary the effective opening to the space, according to the rate of refuse discharge.

18. A self-feeding furnace, comprising separated walls forming the sides of a fuel-feeding passage, and having air outlets arranged to direct air across such passage, said walls being movably mounted, means for placing fuel in one end of the passage below said outlets, mechanism for moving the walls longitudinally of the passage to feed the fuel and refuse, a plate arranged in rear of said passage to receive the refuse of fuel fed therefrom, pushing means connected with the fuel-feeding walls, and moved thereby across the plate, and means for placing and maintaining the plate at an inclination downward and rearward from said pushing means.

19. In a furnace, fuel-supporting surfaces and air-supplying means, a plate pivoted on a horizontal axis adjacent to the discharge end of said fuel-supporting surfaces adapted to receive matter discharged therefrom, means for holding said plate at any one of a number of adjustments angularly about its axis, a wall located near the swinging edge of the plate arranged to provide an opening above such swinging edge, and a shutter pivotally mounted at the top of such opening in rear of the termination of the plate so as to cross the opening, and means yieldingly impelling the shutter toward the plate.

20. In a furnace, fuel supporting surfaces and air-supplying means, a plate pivoted on a horizontal axis adjacent to the discharge end of said fuel-supporting surfaces adapted to receive matter discharged therefrom, a wall located near the swinging edge of the plate arranged to provide an opening above such swinging edge, adjusting means for placing and holding said plate in a variety of positions angularly about its axis, and a shutter pivotally mounted at the top of such opening in rear of the plate so as to cross the opening, and a weight connected to the shutter in a manner such as to force it yieldingly toward the plate and normally hold it at an inclination toward the rear end of the plate.

21. In a furnace, a fuel burning retort including in its construction a stationary bottom and movable sides, said sides being movable independently of one another in a forward and rearward direction for feeding fuel, and having provisions for escape of air to support combustion of the fuel, and mechanism for so moving the said walls.

22. In a furnace, a fuel burning retort including in its construction a stationary bottom and movable sides, said sides being movable independently of one another in a for-

- ward and rearward direction for feeding fuel, and having provisions for escape of air to support combustion of the fuel, and mechanism for so moving the said walls including driving devices independently connected to the different walls and independently adjustable whereby to give a greater or less extent of movement to either wall as compared with the movement of the other.
23. In a furnace, including a fuel burning retort having an admission opening at one end, air-supplying means beyond and below the opposite end of such retort, a refuse depository beyond and below said air-supplying means, a fuel pusher connected with said air-supplying means and movable therefrom over said depository, means for moving said air-supplying means and pusher back and forth over said depository, said means being adjustable to vary the extent of movement of said pusher, and means for adjusting said depository to vary the quantity of refuse which can remain thereon.
24. In a furnace, a fuel burning passage composed of a stationary bottom and walls rising above such bottom at each side thereof, said walls being constructed and arranged to having air outlets and being movable in opposite directions, and the opposite walls of the retort being separate from each other and separately movable, and means for moving said walls back and forth and distribute the fuel.
25. In a furnace, a plurality of retorts arranged side by side and having bounding walls, the walls between the adjacent retorts being connected together in a unit structure and being movable as a unit, said walls being constructed and arranged to confine air under pressure and having outlets for aerating the burning fuel in the furnace, and means for moving the wall structure between the retorts back and forth to feed and distribute fuel.
26. In a furnace, a plurality of fuel burning retorts arranged side by side, said retorts having bounding walls, the walls between the retorts being formed into a single air conduit having a longitudinal opening at its upper side, and discharge members or nozzles mounted over the open side of said conduit and constructed to direct air across the retorts at both sides thereof.
27. In a furnace, a plurality of fuel burning retorts arranged side by side and having side walls, the walls at the adjacent sides of adjacent retorts being separated to provide an air space and being connected together to move as a unit, air emitting means carried by the said adjacent walls, and means for moving said walls back and forth to feed and distribute the fuel.
28. In a furnace, a fuel burning retort constructed to cause preliminary distillation of fuel before ignition, means for feeding fuel into one end of said retort beneath the ignited fuel, a depository arranged at the rear of said retort to receive the residue of the fuel issuing from the retort, pushing means arranged to travel over said support to displace refuse across the same, means for adjusting the extent of movement of said pushing means relatively to the movement of the fuel feeding means, and means for adjusting said support so as to govern the discharge capacity of the furnace in accordance with the rate of accumulation of refuse.
29. In a furnace having a fuel burning retort with aerating means arranged for preliminary distillation before ignition of the fuel, means for feeding fuel into one end of the retort, a refuse depository mounted adjacent the opposite end of the retort to receive the incombustible residue of fuel issuing therefrom, pushing means movable over said depository for displacing fuel across the same, adjustable driving means for giving a regulated extent of movement to said pushing means in accordance with the rate of accumulation of the refuse, and means for adjusting said depository to vary the capacity for discharge of refuse in accordance with the rate of disposal thereof by said pushing means.
30. In a furnace having a fuel burning retort, a means for propelling fuel through the same, a plate for receiving refuse pivoted at the rear of the retort on a horizontal pivot, means for propelling refuse across the retort, a rear wall near the free edge of said plate formed and located to provide an opening between itself and the plate, means for tilting and holding said plate so as to vary the effective area of such opening, and a swinging shutter mounted to extend across said opening and yieldingly held toward said plate in a manner permitting its displacement by the advancing refuse.
- In testimony whereof I have affixed my signature, in presence of two witnesses.
- ROBERT SANFORD RILEY.
- Witnesses:
- ARTHUR H. BROWN,
P. W. PEZZETTI.
